DISPLAY BOX FOR WRITING INSTRUMENTS OR OTHER ELONGATED ARTICLES

Alvin A. Kahn, Englewood Cliffs, N.J., assignor to David Kahn, Inc., Hudson County, N.J., a corporation of New Jersey

Filed Oct. 19, 1959, Ser. No. 57,971

Term of patent 14 years

(Cl. D58—13)

FIG. 1

FIG. 2

FIG. 4

Fig. 1 is a top plan view of a display box for writing instruments or other elongated articles,

Fig. 2 is a side elevational view thereof,

Fig. 3 is a bottom plan view thereof, and

Fig. 4 is a transverse vertical section taken on the line 4—4 of Fig. 1, but with the transparent cover in place as in Fig. 2.

I claim:

The ornamental design for a display box for writing instruments or other elongated articles, substantially as shown.
